(57) **CLAIM**

The ornamental design for a tabletop media center with an interchangeable module, as shown and described.

DESCRIPTION

FIG. 1 shows a front-top perspective view of a tabletop media center with an interchangeable module with a top cover in a closed position, according to a first embodiment. FIG. 2 shows a top view of the embodiment of FIG. 1 with the top cover in a closed position.

FIG. 3 shows a front view of the embodiment of FIG. 1 with the top cover in a closed position.

FIG. 4 shows a rear view of the embodiment of FIG. 1 with the top cover in a closed position.

FIG. 5 shows a left side view of the embodiment of FIG. 1 with the top cover in a closed position.

FIG. 6 shows a right side view of the embodiment of FIG. 1 with the top cover in a closed position.

FIG. 7 shows a front-top perspective view of the embodiment of FIG. 1 with the top cover in an opened position exposing the interchangeable module.

FIG. 8 shows a rear-top perspective view of the embodiment of FIG. 1 with the top cover in an opened position exposing the interchangeable module.

FIG. 9 shows a top view of the embodiment of FIG. 1 with the top cover in an opened position exposing the interchangeable module.

FIG. 10 shows a front-top perspective view of a tabletop media center with an interchangeable module with a top cover in an opened position, according to a second embodiment, wherein the design with the top cover in a closed position is identical to the first embodiment shown in FIGS. 1-6.

(Continued)

FIG. 11 shows a rear-top perspective view of the embodiment of FIG. 10 with the top cover in an opened position exposing the interchangeable module; and,

FIG. 12 shows a top view of the embodiment of FIG. 10 with the top cover in an opened position exposing the interchangeable module.

The broken lines in the figures depict portions of the tabletop media center with the interchangeable module that form no part of the claimed design.
